UNITED STATES PATENT OFFICE.

GEORGE C. GARDNER, OF CHICAGO, ILLINOIS, ASSIGNOR TO DAVID NICKEL,
OF MORRIS, ILLINOIS.

DESIGN FOR A HOOK FOR WINDOW-SASH FASTENERS.

SPECIFICATION forming part of Design No. 34,689, dated June 25, 1901.

Application filed April 27, 1901. Serial No. 57,835. Term of patent 7 years.

To all whom it may concern:

Be it known that I, GEORGE C. GARDNER, a citizen of the United States of America, residing at Chicago, in the county of Cook and State of Illinois, have invented and produced a certain new and original Design for Hooks for Window-Sash Fasteners, of which the following is a specification.

In the drawings, Figure 1 is a perspective. Fig. 2 is a plan view, and Fig. 3 is an edge elevation.

Referring to the drawings, A is a flat portion, a a downturned flange extending along a part of its edge, and a' a flange projecting inwardly from the flange a from a² to a³.

Above the flat portion A rises a convex annular part a⁴, perforated at a⁵, and the outline of the flat portion from a⁶ to a⁷ is eccentric to the perforation a⁵.

The essential feature of my design I consider to be the eccentric flanges a a'.

I claim as new and desire to secure by Letters Patent—

The design for a hook for window-sash fasteners, substantially as shown and described. 25

GEORGE C. GARDNER.
